PUMP MECHANISM

Paul B. Barnett and Clarence G. Upton, Freer,
Tex.; said Upton assignor to John P. Muller,
Fort Worth, Tex.

Application September 8, 1938, Serial No. 228,986

5 Claims. (CL 103—180)

This invention relates to pumps and pumping equipment and it has particular reference to oil well pumps especially adapted to the production of oil in areas where the petroleum is 5 pregnated with sand and its principal object resides in the provision of an assembly of parts combined into a compact unit capable of being installed or removed from the well without pulling the tubing yet affording an efficient medium 10 through which maximum production can be maintained under most unfavorable substrata conditions.

Another object of the invention is manifest in the provision of a pumping unit wherein is employed a combination of elements through which many of the conventional features of ordinary pumps are eliminated and whereby greater efficiency and economy in operation will result since the normal wear, under conditions commonly 20 regarded as extremely difficult, is greatly minimized and which is due mainly to the provision of packing rings of a novel design and arrangement.

Still another object of the invention resides in the provision of a pump of the character described embodying certain features of self lubrication whereby considerable of the wear on the working parts is eliminated and thus the device may be operated a longer duration of time without attention.

Yet another object of the invention resides in the provision of a pump assembly especially adapted to the production requirements in areas producing light gravity petroleum and which, due 35 to its peculiar characteristics, cannot be economically handled by equipment employing conventional cups because of the usual slippage and loss occasioned by the use of such equipment. Moreover, high gravity oil or oil having a light 40 body possesses little lubricating qualities and it becomes necessary to provide other means for lubrication of the parts. Such oil often contains injurious chemical properties which react unfavorably upon conventional cups.

45 Broadly, the invention seeks to comprehend the provision of a pump for producing oil possessing many novel features conducive to greater economy in operation and endurance as well as affording a unit capable of installation and removal with the minimum of effort and expense.

While the foregoing objects are paramount, other and lesser objects will become manifest as the description proceeds taken in connection with the appended drawing wherein:

55 Figure 1 is a fragmentary elevational view of

the device positioned within a portion of tubing or casing.

Figure 2 is a vertical sectional view of the invention.

Figure 3 is a lateral sectional view taken on lines 3—3 of Figure 1, and

Figure 4 is a modification wherein the check valve which cooperates with the plunger is positioned within a hold down assembly.

Continuing with a more detailed description 10 of the drawing, the numeral 1 generally designates a section of tubing or casing which has at its lower end a shoe 2 for supporting a hold down assembly 3.

A hollow or tubular plunger 4 is threaded 15 secured to the hold down 3, thus providing a communication with the lower part of the well. The upper end of the plunger 4 has a check valve 5, which may be of the ball check type, threaded thereon, as illustrated in Figure 2.

20 A tubular shell or housing 6 encloses the upper portion of the plunger 4 and has a ball check 7 threadedly attached at its upper end, the latter being provided with threads 8 for engagement with the lower end of a string of sucker rods, 25 not shown.

An important feature of the device is a grease chamber 9, the latter being formed by threadedly attaching a pair of bushings 10 and 11 within the shell 6. The upper bushing 10 is provided 30 with external threads 12 and 13 at its upper and lower ends and has an annular recess 14 in which there is positioned a spring 15 which urges a junk ring 16 upwardly against annular packing rings 17, the latter being retained in place by a threaded packing gland 18 in the upper end of the said bushing.

The lower bushing 11 is threaded to the lowest end of the shell 6 and likewise slidably engages the plunger 4. The lower end of the 40 bushing 11 is provided with a larger packing gland 19 and has opposingly arranged wings 20 integral with its lower side for engagement with recesses 21 of the hold down assembly 3, as particularly illustrated in Figure 2. Another annular recess 22 is provided within the lower bushing 11 and has a spring 23 positioned around the plunger 4 for urging a junk ring 24 against packing rings 25.

Within the chamber 9 there is formed a pair 50 of internal flanges 26 integral with the shell 6, the purpose of which is to engage springs 27 for urging a pair of junk rings 28 against annular packing rings 29. The bushings 10 and 11 provide stops against movement of the packing 55

thereby causing the latter to slidably engage the plunger 4 and thus sealing the chamber 9.

A pair of plugs 30 and 31 are threadedly engaged within the wall of the shell 6 between the flanges 26, one of which is used for injecting lubrication within the chamber 9, whereas the other plug is removed during the filling operation to allow air to escape.

The modification illustrated in Figure 4 differs from the structure shown in Figures 1 and 2 in that the ball check 5 is eliminated from the upper end of the plunger 4 and is provided with a conventional check of another type 32 within the hold down assembly 3. Obviously, the ball check 32 may be positioned below the hold down assembly 3 at any desirable elevation within the tubing 1.

In operation a reciprocating movement is imparted to the shell 6. The shell valve 7 is automatically closed and the liquid is drawn through the plunger 4 and its check 5 or 30, into the upper portion of the said shell. In the downward movement the contents of the upper portion of the shell close the plunger valve 5, thus expressing the liquid out through the shell check 7 and into the tubing 1. Since the plunger 4 is spaced from the shell 6, the sand in the oil cannot affect the working parts except at the packing. The outer packing 17 and 25 clears the plunger 30 of excess sand, thereby preventing undue wear on the packing 29 within the chamber 9.

Manifestly, the structure herein shown and described is capable of considerable changes and modifications from time to time by those skilled in the art and such changes and modifications as may be resorted to falling within the spirit and intent of the invention may also be considered as falling within the scope of the appended claims.

40 What is claimed is:

1. In a pump for oil wells having a stationary tubular plunger and a hold down assembly, a tubular housing operatively receiving the said plunger and adapted to reciprocation thereon, a grease chamber in the said housing around the

5 said plunger, packing arranged in each end of the said grease chamber, check valves on the upper ends of the said plunger and the said housing and resilient retaining means for the said packing in the said chamber.

2. In combination with a string of rods and a pump for oil wells the said pump having a stationary tubular plunger attached to a hold down assembly and a reciprocating shell secured to the said rods receiving the said plunger, a grease 10 chamber in the said shell around the said plunger, means closing each end of the said grease chamber, packing secured in each end of the said chamber and tension means retaining the said packing in circumferential engagement with the 15 said plunger.

3. In combination with a string of rods and a pump for an oil well, the said pump having a stationary plunger and a shell attached to the said rods and slidably embracing the said plunger, 20 a grease chamber in the said shell around the said plunger, packing arranged in each end of the said grease chamber and means within the said chamber urging the said packing into engagement with the said plunger. 25

4. In an oil well pump adapted for operation with a string of rods, the said pump having a stationary plunger attached to a hold down assembly and a reciprocable shell operating on the said plunger and attached to the said rods, a 30 grease chamber in the said shell, packing arranged in each end of the said chamber and tensioned means bearing against the said packing urging the same into circumferential engagement with the said plunger. 35

5. In an oil well pump and a string of rods, the said pump comprising a stationary plunger and a hold down assembly and a reciprocating shell attached to the said rods receiving the said plunger, a grease chamber in the said shell, packing 40 means positioned in each end of the said chamber adapted to engage the said plunger and tensioned means bearing against the said packing. 40
